UNITED STATES PATENT OFFICE.

WILLIAM AUGUSTUS PENTECOST, OF WORCESTER, MASSACHUSETTS.

MECHANICAL MOVEMENT.

SPECIFICATION forming part of Letters Patent No. 761,538, dated May 31, 1904.

Application filed October 2, 1902. Serial No. 125,622. (No model.)

To all whom it may concern:

Be it known that I, WILLIAM AUGUSTUS PENTECOST, a citizen of the United States, residing at Worcester, in the county of Worcester and Commonwealth of Massachusetts, have invented a new and useful Mechanical Movement, of which the following is a specification.

My invention relates to improvements in mechanical movements employed in furnishing power for various purposes in which certain peculiar mechanism adapted to utilize gravity through the medium of weights forming a part of said mechanism and arranged so as to be capable of being relatively changed in a predetermined manner to produce results similar to those produced by other motors and engines is used, as hereinafter described and claimed; and the objects of my improvement are, first, to provide mechanism whereby weights are utilized in an efficient and practical manner for moving ponderable bodies located either near to or at a distance from said mechanism; second, to afford a safe and durable substitute for an ordinary motor or engine which is capable of practical operation when applied to an elevator or to other devices of a similar nature or of such a nature as to render this invention applicable thereto and which is simpler and less expensive to operate than other engines or motors used for a like purpose, and, third, to embody my improved mechanical movement in a working machine or engine practicable for such uses as it may be adapted, a conspicuous example being the running of an elevator. I attain these objects by the mechanism illustrated in the accompanying drawings, in which—

Figure 1 is a side view of my improved mechanism, showing its application to an elevator, the movement being normally disposed, as when the elevator-car is half-way between the extreme limits of its travel; Fig. 1^a, a part of Fig. 1, showing the car and upper supporting and operating members; Fig. 2, a similar view showing the position of the parts when the movement is at one end of what may be termed its "stroke;" Fig. 3, a view showing said mechanism at the other end of its stroke; and Fig. 4, an end view of certain parts of the mechanism, the major weight being shown in section.

Although the mechanical movement herein set forth is illustrated in connection with an elevator, and I consider it particularly adapted for this use, it is to be understood that it may be advantageously employed in other capacities.

Referring now to the drawings, in which similar figures designate similar parts throughout the several views, I will first proceed to describe the movement itself.

A walking-beam 10, mounted on trunnions or a shaft 11, which is journaled in and supported by a suitable framework 12, is provided with a depending arm 13, rigidly attached to the under edge thereof, the center of said arm being in line with the center of said shaft and at right angles to the longitudinal axis of the walking-beam. The walking-beam 10 is further provided with a curved track 14 on one side and a substantially straight track 15 on the other side. The track 14 preferably consists of two arcs or rails separated from each other and securely bolted or otherwise rigidly attached to the walking-beam, as best shown in Fig. 4. I prefer to elevate the track 15 above the walking-beam for the greater part of its length and do this by means of suitable brackets, to which said track is securely attached and which are in turn bolted or otherwise rigidly fastened to said walking-beam. With the exception of one end of the track 15 the tracks 14 and 15 are both situated at one side of the central vertical plane or pivotal center of the walking-beam, the exception noted being that said track 15 extends a short distance in the other direction beyond said plane or center. Of course the tracks 14 and 15, either one or both, may be raised or lowered from their present position as the exigencies of the case demand, and their length may be varied more or less to meet different conditions, there being no objection to lengthening or shortening either of the tracks in either direction; but if the length of the track 14 is increased toward the pivotal center of the walking-beam said track must be lowered so that it can pass beneath the shaft 11, and in order to utilize that portion of said track which passes beneath said shaft in this event it will be seen that a bend in the hanger 16 (presently to be described) is required, so as

to permit the whole length of the track to be utilized.

The hanger 16 is designed to be supported by and move upon the track 14, and what I term the "major" weight 17 is located at the base of said hanger. Any suitable means may be employed to afford an easy-running support for the hanger 16 on the track 14, and I show for this purpose a truck 18, provided 5 with rolls 19, which run upon the two arcs or rails which compose the track, and hubs 20, extending from opposite sides of said hanger and resting upon the upper concave edges of said truck. With the exception of the rolls 10 19 the truck 18 moves back and forth between the rails of the track, and the hanger 16 extends between said rails and through said truck some distance above the walking-beam when the same is normally disposed or stands 15 15 with its longitudinal axis in a horizontal position, as shown in Fig. 1. What I term the "minor" weight 21 is attached to the upper end of the hanger 16. A link 22 has one end pivoted at 23 to the major weight 17 and the other 20 end pivoted at 24 to the arm 13 a little distance above the base thereof. The pivot 23 is practically in the center of the weight 17, and the upper edges of the track 14 should 25 correspond with an arc struck from the center of said pivot.

Assuming that the force exerted by the load on the free end of the walking-beam 10 where no tracks are located is equal to that exerted by the hanger 16 and its weights, so that said 30 walking-beam stands horizontally when the hanger 16 is moved so that its support represented by the truck 18 and the hubs 20 travels away from the shaft 11, the equilibrium is overcome, and the walking-beam begins to 35 tilt and to approach the position shown in Fig. 2; but as the point 23 approaches a line dropped from the center of the shaft 11 the power of the weight 17 decreases until only the power exerted by the weight 21 remains to do 40 the work. This loss, however, is compensated for in a manner and by the means hereinafter described. On the other hand, when the hanger 16 is moved from the position shown in Fig. 1; so that its track-support approaches 45 the shaft 11, the balance is overcome and the preponderance of power is shifted to the free end of the walking-beam, or rather to the load attached to the same. The result of this last action is to cause the parts to tend toward an 50 assumption of the position shown in Fig. 3, the power of the weights 17 and 21 being minimized as the change in position takes place until the weight 21 passes the vertical central plane of the shaft 11, when said weight 55 passes to the assistance of the load. The compensating means above referred to is also utilized to bring the parts into the extreme position shown in Fig. 3, because of the impossibility of entirely eliminating the weight 60 17 as a factor now on the wrong side of the

center of gravity. The hanger 16 is free to turn upon the pivot 23 and the link 22 upon the pivot 24; but the centers represented by said pivots can never approach each other. Hence it is possible to obtain the effects described by changing the position of the track-support of said hanger. What is true when the track-support of the hanger 16 is moved from the intermediate position in either direction is also true, although in a less degree, 70 when said support is moved away from either of its extreme positions—that is to say, when said support is adjacent to the end of the walking-beam by moving it toward the center that end of the walking-beam begins to 75 rise and when the support is at the other end of its travel and is moved away from the center the same end of the walking-beam begins to descend.

In order to make up for the loss referred 80 to in the preceding paragraph, what may be termed a "compensating" weight is employed, the same preferably consisting of a heavy roll 25, arranged to travel upon the track 15. The roll 25 is mounted in the end of a rod 26, 90 the opposite end of which is pivoted to the upper end of a lever 27, pivoted at 28 to the framework 12 and having its lower end connected with the base of the arm 13 below the pivot 24 by means of a link 29. The parts 95 are so arranged that the equilibrium of the walking-beam 10 is theoretically maintained only when the centers of the weight 21, roll 25, hub 20, and pivot 23 are in the same vertical plane, the weights being necessarily 100 commensurate with the load. It should be stated in this connection that in the description previously given of the operation of the walking-beam and hanger the load must be less in the absence of the compensating weight 105 25, in order to secure the equilibrium there described, than when such weight is used. It is believed that the movement is not as practical without the compensating weight, and the aforesaid description was intended merely 110 to explain the theoretical operation of the parts described up to that point. Assuming now that the hanger 16 is shifted so as to depress the track end of the walking-beam, the roll 25 will be moved outward on the track 115 15 through the medium of the arm 13, lever 27, and connecting parts, and said roll adds its weight to that exerted by the weights 17 and 21, being actuated farther away from the center as the weight 17 approaches the center 120 and begins to lose its power, until the parts stand as shown in Fig. 2. By changing the direction of the hanger 16 it will be readily seen that the roll 25 must begin at once to approach the center and to exert less and less 125 power until it passes the center into the position shown in Fig. 3, when its power is added to that of the load.

The load in this case is represented by the elevator-car 30, suspended from a cable 31, 130

which passes over a sheave 32, suspended in the usual manner, to a large pulley 33, tight on a shaft 34, suitably journaled in the framework 12. The lower end of the cable 31 is securely fastened to the pulley 33. A cable 35 is attached at one end to the free end of the walking-beam 10 and at the other end to a small pulley 36, tight on the shaft 34. The pulleys 33 and 36 are normally prevented from revolving by means of a suitable brake, in this case consisting of a disk 37, tight on the shaft 34, a band 38 passing around said disk and having one end fastened to an upright 39 and the other end to a lever 40, which is pivoted to said upright and has a weight 41 suspended therefrom. The weight 41 draws down the lever 40 and tightens the band 38 on the disk 37, thereby producing sufficient frictional contact to hold the parts connected with the pulleys 33 and 36 immovable. A rope 42, suspended from the top of the elevator-well, passes through the car 30 and is attached to the end of the lever 40. As a convenient means of shifting the hanger 16 a shifter-rod 43 is pivoted at one end to said hanger below the track 14 and at the other end to an arm 44, forming part of a reversing-reel 45, which is mounted on a shaft 46, suitably journaled in a framework 47. A rope 48 passes over a sheave 49, supported in a similar manner as the sheave 32 at the top of the elevator-well, and has its lower ends fastened to opposite sides of the reel 45. One reach of the rope 48 passes through the car 30, and the necessary tension is provided for said rope by means of sheaves 50, 50, bracketed beneath the first floor in any convenient manner.

If the diameters of the pulleys 33 and 36 are as two to one, it will be necessary for the free end of the walking-beam to describe an arc the chord of which is one-half the distance that the car is to travel in order to raise or lower said car the required distance, and the weight required to raise the maximum load must be approximately twice that of the car when loaded. It is obvious, however, that these proportions may be changed, and if they are as six to one the practicability and efficiency of the mechanism are not impaired, but, on the contrary, are increased.

The car 30 is operated from the inside in the following manner: To cause it to ascend, pull downward on that part of the rope 48 which passes through the car and at the same time pull upward on the rope 42, in order to partly or wholly release the pulleys 33 and 36 from the brake, according to the amount of load relative to the weight. The movement given to the rope 48 rotates the reel 45 to the right, and this moves the shifter-rod 43 and the hanger 16 in the same direction. The car at once begins to ascend and continues on its upward course until the brake is again applied by being entirely released to the influence of the weight 41 or the walking-beam arrives at

the end of its lifting stroke, when further upward movement of the car ceases. To descend, pull upward on the rope 48 and partly release the brake. The reel 45 is this time rotated to the left by the rope 48 and draws the hanger 16 over to the center by means of the rod 43. The car now descends under the control of the brake and may be stopped by the same at any point desired, or if allowed to reach the bottom, the walking-beam then having completed its stroke in the other direction, all further motion ceases. In manipulating the car it should generally be controlled and governed by the brake in order to insure steadiness and evenness of movement, and for the further reason that in practice the weights which furnish the power are in excess of the maximum load to the extent needed to raise the same and overcome frictional resistance as well as they should also be great enough to lift the maximum load at the desired speed. Hence without the controlling influence of the brake a load less than the maximum would be propelled upward with too much swiftness.

A stop 51 may be mounted on the framework 12 in such a position as to receive the weight 17 at the end of its inward travel, and thus prevent liability of breaking or disarranging the mechanism.

The weight 17 may be formed in part of separable slabs held to the base of the hanger 16 by means of pins 52, projecting from said base, a convenient method of increasing or decreasing the weight being thus furnished.

The ends of the track 15 may be curved upward more or less for the purpose of checking the roll 25 at the extreme limits of its travel, and this curvature, especially if it approaches the horizontal when the walking-beam is tilted, also serves in a measure to decrease the power required to shift the parts, since said roll can be more easily started from such a position than when it has to be moved initially up an inclined plane. This is a detail of construction not thought to be of vital importance, but is mentioned herein as one of various modifications which will suggest themselves to one skilled in the art.

The shifter-rod 43 may be pivotally connected with the hanger 16 above instead of below the track 14, if desired, and the walking-beam may have arms or sections of unequal length. These and other changes of minor importance, including those hereinbefore mentioned, may be made without departing from the nature of my invention, which I seek to cover broadly. I do not wish to be restricted to the exact construction herein shown and described, but desire to include all modifications falling within the scope of my invention and claims.

What I claim as my invention, and desire to secure by Letters Patent, is—

1. A mechanical movement comprising a member pivotally mounted between its ends, a

- weighted member suspended from and slid-
ingly mounted on said first-mentioned mem-
ber, and automatic means for controlling the
swing of said weighted member.
- 5 2. In a mechanical movement, a track adapt-
ed to rock, a member slidingly mounted there-
on, and a second member pivotally mounted on
the first and having weights above and below
said track, the swinging motion of the second
10 member being independent of the rocking motion
of the track.
3. In a mechanical movement, a member
pivotally mounted between its ends and pro-
vided with a track, a suspended member slid-
15 ily mounted on said track, and automatic
means for controlling the swing of said sus-
pended member.
4. In a mechanical movement, a member
pivotally mounted between its ends, a second
20 member suspended from the first, automatic
means for controlling the swing of said second
member, weights carried by the second mem-
ber, and means adapted to shift said weights
relative to the pivotal point of the first mem-
25 ber.
5. In a mechanical movement, a member
pivotally mounted between its ends, a second
member suspended from the first, automatic
means for controlling the swing of said second
30 member, weights carried by the second mem-
ber, and means adapted to shift said weights
relative to each other and to the pivotal point
of the first member.
6. In a mechanical movement, a member
35 pivotally mounted between its ends, a second
member suspended from the first, automatic
means for controlling the swing of said second
member, weights carried by the second mem-
ber, means adapted to shift said weights rela-
40 tive to the pivotal point of the first member,
and a compensating weight movably mounted
on the latter.
7. A mechanical movement comprising a
45 member pivotally mounted between its ends
and provided with a projection, a weighted
member suspended from the first, the point of
suspension being movable, and a pivotal con-
nection between said suspended member and
50 projection.
- 50 8. A mechanical movement comprising a
member pivotally mounted between its ends
and provided with a projection, and a weighted
swinging member slidingly mounted on said
first-mentioned member and pivotally con-
55 nected with said projection.
9. A mechanical movement comprising a
member pivotally mounted between its ends
and provided with a projection, a weighted
member suspended intermediate of its termi-
60 nals from the first, the point of suspension being
movable, and a pivotal connection between
said suspended member and projection.
10. A mechanical movement comprising a
65 member pivotally mounted between its ends
and provided with a projection, a second mem-
- ber suspended intermediate of its terminals
from the first, the point of suspension being
movable, weights mounted on said suspended
member above and below its point of support,
and a pivotal connection between said sus-
70 pended member and projection.
11. A mechanical movement comprising a
member pivotally mounted between its ends,
a weighted member suspended intermediate
of its terminals from the first, the point of
suspension being movable, and a movable
75 compensating weight, the parts being arranged
so that the centers of the weights shall be in
the same vertical plane with the center of the
point of suspension only once while the latter
is passing from one end of its course to the
80 other.
12. A mechanical movement comprising a
member pivotally mounted between its ends
and provided with a projection, a weighted
swinging member slidingly mounted on said
first-mentioned member and pivotally con-
85 nected with said projection, and a compensating
weight movably mounted on said first-
mentioned member and also pivotally con-
90 nected with the projection.
13. A mechanical movement comprising a
member pivotally mounted between its ends
and provided with a projection, a weighted
member suspended intermediate of its termi-
95 nals from the first, the point of suspension
being movable, a movable compensating
weight, and pivotal connections between said
projection and the suspended member and
compensating weight, the parts being arranged
100 so that the centers of the weights shall be in
the same vertical plane with the center of the
point of suspension only once while the latter
is passing from one end of its course to the
other.
14. The combination with a walking-beam
suitably mounted and means to control a load
connected with the free end of the same, of a
weighted member suspended from and slid-
105 ily supported by said walking-beam, and
automatic means for controlling the swing of
said weighted member.
15. The combination with a walking-beam
suitably mounted and means to control a load
connected with the free end of the same, of a
weighted member suspended from and slid-
110 ily supported by said walking-beam, adapt-
ed to swing independent of the rocking motion
of the latter, and a compensating weight mov-
ably mounted on the walking-beam.
16. The combination with a walking-beam
suitably mounted and a load connected with the
free end of the same, a weighted member sus-
pended from and shiftingly supported by said
walking-beam adapted to swing independent
115 of the rocking motion of the latter, and means
adapted to be operated at some remote point
to shift said member.
17. The combination with a walking-beam
suitably mounted and means to control a load
120

connected with the free end of the same, of a weighted member suspended from and shiftingly supported by said walking-beam adapted to swing independent of the rocking motion 5 of the latter, and means adapted to be operated at a remote point to shift said member.

18. The combination with a walking-beam suitably mounted and provided with a depending arm and a track, of a weighted swinging 10 hanger slidingly supported by said track and pivotally connected with said arm.

19. The combination with a walking-beam suitably mounted and provided with a depending arm and a track, of a swinging hanger slidingly supported by said track and pivotally connected with said arm, and weights mounted 15 on said hanger above and below its point of support.

20. The combination with a walking-beam 20 suitably mounted and provided with a depending arm and a track, of a truck adapted to travel upon said track, and a hub-provided weighted hanger carried by said truck and pivotally connected with said arm.

21. The combination with a walking-beam suitably mounted and provided with a depending arm and tracks, of a weighted swinging hanger slidingly supported by one of said tracks and pivotally connected with said arm, 30 and a compensating weight mounted to move on the other track and also pivotally connected with the walking-beam arm.

22. The combination with a walking-beam suitably mounted and provided with a depending arm and tracks one of which latter projects 35 beyond the other, of a weighted swinging hanger slidingly supported by one of said tracks and pivotally connected with said arm, and a compensating weight mounted to move 40 on the other track and also pivotally connected with the walking-beam arm.

23. The combination with a walking-beam suitably mounted and provided with a depending arm and a curved and a substantially 45 straight track, of a weighted swinging hanger slidingly supported by said curved track and pivotally connected with said arm, and a compensating weight mounted to travel on said straight track and also pivotally connected 50 with said arm.

24. The combination with a walking-beam suitably mounted and provided with a depending arm and a curved track, of a weighted swinging hanger slidingly supported by said 55 track and pivotally connected with said arm, the supporting edge of the track being in conformity with an arc struck from the hanger end of the pivotal connection.

25. In combination, a walking-beam suitably mounted, weights supported by said walking-beam, one of said weights being suspended 60 from the latter, means to change the positions of said weights relative to each other and

to the walking-beam support, and means to connect a load with the free end of the walking-beam, comprising pulleys of different sizes. 65

26. In combination, a walking-beam suitably mounted, weights supported by said walking-beam, means to change the positions of 70 said weights relative to each other and to the walking-beam support, means to connect a load with the free end of the walking-beam, comprising pulleys of different sizes, and a brake adapted to control said pulleys.

27. In combination, a walking-beam suitably mounted and provided with a depending arm, a weighted hanger slidingly supported 75 by said walking-beam and pivotally connected with said arm, a reversing-reel suitably mounted, and a shifter-rod between said reel and hanger.

28. In combination, a walking-beam suitably mounted and provided with a depending arm, a weighted hanger slidingly supported by said walking-beam and pivotally connected 85 with said arm, a compensating weight movably supported by the walking-beam and also pivotally connected with the arm, a reversing-reel suitably mounted, and a shifter-rod between 80 said reel and hanger. 90

29. In combination, a walking-beam suitably mounted and provided with a depending arm, a weighted lever slidingly supported by said walking-beam and pivotally connected with said arm, a compensating weight movably supported by the walking-beam and also 95 pivotally connected with the arm, a reversing-reel suitably mounted, a shifter-rod connected with said reel and hanger, and means to connect a load with the free end of the walking-beam, comprising differential pulleys. 100

30. In combination, a walking-beam suitably mounted and provided with a depending arm, a weighted lever slidingly supported by 105 said walking-beam and pivotally connected with said arm, a compensating weight movably supported by the walking-beam and also pivotally connected with the arm, a reversing-reel suitably mounted, a shifter-rod connected with said reel and hanger, means to connect a load with the free end of the walking-beam, comprising differential pulleys, and a 110 brake for controlling said pulleys.

31. In combination, a walking-beam suitably mounted, a hanger slidingly mounted on 115 said walking-beam, automatic means for controlling the swing of said hanger, a weight at the lower end of said hanger, and means to increase or decrease said weight.

In witness whereof I have signed my name 120 to this specification in the presence of two subscribing witnesses.

WILLIAM AUGUSTUS PENTECOST.
